UNITED STATES PATENT OFFICE.

HENRY F. BAILEY, OF DENVER, COLORADO, ASSIGNOR OF ONE-HALF TO
LONZO E. STEELE AND HARRY E. SIMS, OF DENVER, COLORADO.

NON-REFILLABLE BOTTLE.

SPECIFICATION forming part of Letters Patent No. 708,981, dated September 16, 1902.

Application filed January 6, 1902. Serial No. 88,606. (No model.)

To all whom it may concern:

Be it known that I, HENRY F. BAILEY, a citizen of the United States of America, residing at Denver, in the county of Arapahoe and State of Colorado, have invented certain new and useful Improvements in Non-Refillable Bottles; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to improvements in non-refillable bottles.

The object of the invention is to produce a bottle the neck of which is provided internally and at its lower end with a valve-seat in which normally rests a spherical valve or ball, while the upper end of said neck receives a channeled plug the lower half of which is reduced in diameter and forms a depending portion the extremity of which is a suitable distance above the spherical valve and prevents excessive movement of the same in one direction, while a series of projections or lugs which surround the valve-seat act in conjunction with the depending portion of the channeled plug to confine the spherical valve or ball to the lower end of the neck of the bottle, but at the same time allowing it to move far enough from its seat to permit the passage of liquid through the said seat when the bottle is tilted. The channels in the plug are zigzag, which will prevent the insertion of a wire, thus making it impossible to tamper with the valve.

20 The invention further consists in the novel construction and arrangement of the parts constituting the same, as will be fully set forth in the accompanying specification and claims.

In the accompanying drawings, forming part of this application, Figure 1 is a vertical sectional view through the neck of a bottle, showing a channeled plug secured in the upper end thereof and a ball-valve seated in the lower end. Fig. 2 is a sectional view 25 taken horizontally on the dotted line 2 of

Fig. 1, showing a projection formed integral with the neck of the bottle, which engages a notch in the channeled plug to properly position the said plug. Fig. 3 is a sectional view taken horizontally on the dotted line 3 3 55 of Fig. 1, showing the valve-seat and surrounding projections or lugs which confine the ball-valve within certain limits. Fig. 4 is a perspective view of the channeled plug, clearly showing the notch which engages the integral projection formed in the neck of the bottle; and Fig. 5 is a sectional perspective view of the upper portion of the neck of the bottle, showing the integral projection which lies in the notch of the channeled plug. 60

65 Like letters indicate corresponding parts in the several views.

Referring to the drawings, the letter A indicates the neck of a bottle the throat of which is contracted in diameter at its lower end to form a valve-seat *a*, in which is seated a ball-valve *b*, which is preferably made of glass and is ground so as to be perfectly spherical in order to properly fit its seat *a*, which also may be reamed or ground. The ball, however, may be made of metal or of rubber, if so desired. Around the valve-seat and arranged so as to confine the ball-valve within certain limits is a series of projections or lugs *c*, preferably four in number, which 70 inclose the said valve, but do not contact with it, thus allowing the valve to leave its seat when the bottle is tilted. Between the lugs *C* are passages *C*², as fully shown in Figs. 1 and 3, through which the liquid flows, as will 75 be hereinafter more fully set forth. The throat tapers from the lugs *C* to a point *d* and from this point to near the mouth is of one diameter, and this portion of the throat forms a chamber *C*³, in which is positioned a 80 channeled plug *F*. At the top of the chamber *C*³ the diameter of the throat is enlarged to form a mouth *f*, in which is fitted a cork *g*, as shown. The plug *F* is of the form shown in Figs. 1 and 4 and comprises a body portion 85 which is of the diameter of the chamber *C*³ and a depending portion *F*², which is of less diameter than the body portion and gradually tapers to its extremity, which is located a slight distance above the ball-valve *b*, as 90 95 100

shown. The periphery of the body portion of plug F is provided with zigzag channels F³, which form a communication between the mouth of the bottle and that portion of the throat below the plug, and through the channels the contents of the bottle passes when the bottle is tilted, as will be fully understood. I have shown three of these channels, though a greater number may be employed, if desired. These channels F³ extend vertically from the top of the plug to near the bottom of the body portion, where they deflect upwardly at an acute angle and then extend vertically downward to the bottom of the body portion, as shown in the drawings, at which point they open out into the throat of the bottle. The lower portions of the channels are thus out of alinement with the upper portions, and the acute upward deflection of each channel will frustrate any attempt to tamper with the ball-valve by means of a wire or any analogous device. In order to properly position the plug F in the neck of the bottle, so that the lower end of its depending member F² may be the required distance above the ball-valve, a notch f³ is formed to one side of one of the channels f² and near the top thereof, and the said notch engages a projection f⁴, formed in the neck of the bottle near the top of chamber C, and when the said notch and projection are in engagement with each other the plug will be properly positioned with respect to the ball-valve. The plugs F are preferably made of glass, though they may be made of any suitable material. There are several ways in which the plug can be secured in the throat in such a manner as to be non-removable, one of which is to coat the plug with a non-liquid-dissolving non-heat-melting cement and then insert it in the throat and allow the cement to harden. Another way would be to insert the plug and then heat both the neck and plug until they are burned or sweated or fused together at one or more points of their surfaces or throughout their entire adjacent surfaces, thus forming a monolithic or integral structure of the neck of the bottle and the plug.

The bottle is filled in the usual manner, after which the ball-valve is dropped in and rests upon seat a. The plug F is then inserted, the surface of its body portion having first been coated with a suitable cement, providing it is deemed advisable to use a cement, and the channel f², having the notch f³, being positioned to slide over projection f⁴. As the plug is pushed downward the projection f⁴ will contact with the upper wall of the deflected portion of the channel, and by turning the plug slightly to the left the projection will then lie in the upper portion of the channel, and by pushing the plug still farther downward until the notch f³ is on a level with projection f⁴ and turning said plug so that its notch shall engage the projection the plug will be locked in its proper position relatively to the position of the ball-valve. When

the cement, if used, has thoroughly hardened or the plug and neck have been fused or burned together, the plug will be rigidly secured within the neck of the bottle and can only be removed by breaking the said bottle, and the projection f⁴ serves not only to properly position the plug, but to hold it in its proper position until the cement has hardened or while it is being burned or fused to the neck. The bottle is now ready for use, and while its contents can be readily poured out it will be impossible to again fill the bottle. The mouth of the bottle is closed by an ordinary cork. When the bottle is tilted, as when a portion of its contents is poured off, the ball-valve will roll from its seat, but will be limited in its movement by the depending member F² of plug F and by the projections or lugs C, which act in conjunction, to so confine the ball that it cannot move more than a slight distance away from its seat. The liquid will then flow out through the seat A and passages C² into the throat of the bottle, thence through the zigzag channels f² in plug F, and out through the mouth of the bottle. As the bottle resumes a vertical position the ball moves quickly to its seat, thus closing the passage to the interior of the bottle and preventing the entrance of any liquid which might be poured in at the mouth of the bottle. It will thus be seen that my device is not only simple and effective, but can be easily and cheaply manufactured. The quick movement of the ball as the bottle resumes a vertical position prevents the entrance of liquid from above, thus making it practically impossible to refill the bottle when it has once been emptied, and the zigzag channels in plug F will prevent any attempt to move the ball from its seat by a wire or any other device.

Having thus described my invention, what I claim as new, and desire to secure by Letters Patent, is—

1. In a non-refillable bottle, the combination of a bottle having a neck and throat portion, a valve-seat in said throat, a spherical valve seated on said valve-seat, a plurality of lugs arranged concentric to said valve-seat, arranged to confine said spherical valve in operative relation to said valve-seat, suitable liquid-passages from said valve-seat between said lugs past said spherical valve, a key in the throat of the neck of said bottle, a plug in the throat of said bottle, arranged to define the operative movement of said valve, a keyway in said plug arranged to fit over said key when said plug is inserted in said throat, and adapted to define the position of said plug relative to said valve, and a zigzag liquid-passage through said plug having a substantially right-angled offset in its course through said plug, substantially as described.

2. In a non-refillable bottle, the combination with a bottle provided with a neck and mouth and throat portion of a suitable valve-seat and valve in said throat, a plug in said throat containing a keyway, a key projecting

from said throat into said keyway and adapted to define the position of said plug relative to said valve, means including a suitable agent for non-removably securing said plug in the neck of said bottle, a liquid-passage through said plug having an offset in its length arranged and adapted to prevent access to said valve from the mouth of said neck, and a suit-

able cork or stopper in the mouth of said throat, substantially as described. ¹⁰

In testimony whereof I affix my signature in presence of two witnesses.

HENRY F. BAILEY.
